UNITED STATES PATENT OFFICE.

ARTHUR JOSEPH NAQUIN, OF ALEXANDRIA, LOUISIANA.

GRATE BAR.

Application filed October 18, 1921. Serial No. 508,525.

To all whom it may concern:

Be it known that I, ARTHUR J. NAQUIN, a citizen of the United States, residing at Alexandria, in the parish of Rapides and 5 State of Louisiana, have invented certain new and useful Improvements in Grate Bars, of which the following is a specification.

This invention relates to improvements 10 in grate bars and more particularly to that type in which the body of the bar is formed with a number of draft perforations arranged in longitudinally extending rows. The formation of these perforations tends 15 of course to weaken the body of the bar, and to counteract this weakening effect, bars of this type are ordinarily provided upon their under sides with longitudinally extending reinforcing flanges which depend from the 20 plane of the body of the bar. Draft is most effectively obtained when the perforations occupy a maximum area of the bar and are uniformly arranged. However in casting the ordinary form of grate bar of this type 25 it is found necessary to so locate and proportion the reinforcing flanges that the number of draft perforations in the bar must be greatly reduced. For example in the intermediate portion of such a bar the 30 draft perforations are arranged in longitudinally extending rows located relatively close to one another, and the perforated area cannot be extended over the entire surface of the bar for the reason that the space between 35 adjacent rows is not sufficient to accommodate a reinforcing flange of the proper dimensions. As a consequence the bar is left imperforate along longitudinal portions where the reinforcing flanges are 40 located and where other rows of perforations would otherwise be provided in obtaining a symmetrical arrangement of such perforations.

In consideration of the foregoing it is the 45 primary object of the present invention to provide a grate bar in which the reinforcing flanges are so formed as to permit of the bar being provided throughout substantially its entire area with draft perforations 50 symmetrically arranged and without any of the perforations being obstructed by the said flanges.

Another object of the invention is to so form the flanges that they will more readily compensate for expansion and contraction of the bar and more effectually reinforce the

same although capable of being formed somewhat thinner than is considered practicable in the case of straight longitudinal flanges. 60

In the accompanying drawing:

Figure 1 is a plan view partly in horizontal section and partly broken away illustrating the grate bar embodying the invention; 65

Figure 2 is a side elevation of the bar. In the drawing the body of the bar is indicated by the numeral 1 and the said body is formed with a plurality of draft openings indicated by the numeral 2. These 70 openings are preferably arranged in longitudinal series located relatively close to one another, and the openings in adjacent series are preferably relatively staggered so that the openings may be formed of maximum 75 diameter and of such number as to distribute them over a maximum portion of the area of the bar. Also the bar 1 is formed in its longitudinal edges with notches 3 which register in adjacent bars when the bars are 80 disposed edge to edge and thus provide additional draft openings and maintain the symmetrical arrangement thereof. At each end the bar 1 is formed upon its underside with depending lugs 4 and with longitudinally extending reinforcing flanges 5. The 85 flanges 5 extend between the lugs 4 longitudinally of the underside of the bar and depend from the plane thereof and by reference to the drawings it will be observed 90 that each flange is given a sinusoidal form and is so arranged that because of this form and the staggered arrangement of the draft perforations, the perforations of adjacent rows will be accommodated within the convolutions of the flanges. Therefore the presence of the reinforcing flanges does not in 95 any way obstruct the passage of air through the perforations and the bar may be uniformly perforated throughout its entire 100 area. Furthermore it is obvious that a reinforcing flange given the form stated will possess greater strength than a straight flange even though formed thinner, and also it is better adapted to compensate for expansion and contraction of the body of the 105 bar.

In order to relatively brace the reinforcing flanges 5, one or more transverse reinforcing flanges 6 are formed upon the underside of the body of the bar and extend between and are integrally connected with 110

the flanges 5 as best shown in Figure 1, and this flange 6 is also preferably of sinusoidal form so as to adapt it to clear the draft openings in its vicinity.

5 From the foregoing description of the invention it will be evident that by reason of the peculiar form given the reinforcing flanges and by reason of the location of these flanges, the body of the bar is effectively reinforced, expansion and contraction is compensated for, and provision is made for the formation of a maximum number of draft perforations in the said body of the bar and their even or symmetrical disposition.

13 Having thus described the invention what is claimed as new is:

1. A grate bar comprising a body with a plain top surface and having draft perforations arranged in straight rows, the perforations in adjacent rows being relatively staggered, spaced solid reinforcing flanges integral with and depending from the under side of the body and positioned

in longitudinal direction of the body between adjacent rows of the perforations, and a transverse reinforcing flange connecting said longitudinally running flanges, all of said flanges being of sinusoidal formation.

2. A grate bar comprising a body with a plain top surface and having draft perforations arranged in rows extending longitudinally with the bar, the perforations in adjacent rows being relatively staggered, supporting lugs at the ends of said body, spaced solid reinforcing flanges integral with and depending from the under side of the body and extending between said supporting lugs, said flanges each positioned along one of the outermost rows of perforations, the convolutions of the flanges corresponding to the contour of the adjacent perforations, and a transverse flange connecting said other flanges, all of said flanges being of sinusoidal form.

In testimony whereof I affix my signature.
ARTHUR JOSEPH NAQUIN. [L. s.]
